UNITED STATES PATENT OFFICE.

ERNEST HOCHMUTH AND VALENTINE TANCZOS, OF CHICAGO, ILLINOIS; SAID HOCHMUTH ASSIGNOR TO SAID TANCZOS.

MILK-BOTTLE-CAP-MAKING MACHINE.

Application filed August 14, 1924. Serial No. 732,045.

The main object of this invention is to provide a machine suitable for the production of bottle caps formed so as to present a crown and an encircling rim, the crown being adapted to be retained in the neck of the bottle by friction and the rim serving the purpose of covering and protecting the edge of the bottle.

Another object is to provide a bottle cap making machine in which bottle caps of the type previously mentioned are formed in a continuous operation in a gang punching and forming press, the punching and forming press being arranged in such plane that the completed caps will fall of their own weight from the machine, eliminating the use of a stripping or removing mechanism.

Still another object is to provide a bottle cap making machine in which various novel features are presented, the foremost of which are an automatic feeding mechanism for moving the sheet material into position for the gang dies, and an additional means of moistening both surfaces of the sheet material before arriving at the gang dies.

These and other novel objects will become apparent in the description below, in which characters of reference refer to like-named parts in the drawing.

Referring briefly to the drawing, Figure 1 is a front elevational view of the bottle cap making machine, showing the various moving elements in direct relation to each other.

Figure 2 is a fragmentary side elevational view as seen from the reverse side of the machine shown in Figure 1, and illustrates the means for feeding the sheet material over the gang blanking dies.

Figure 3 is a top plan view of the bottle cap making machine showing the gang arrangement of the dies and sheet material feeding rolls.

Figure 4 is a fragmentary cross-sectional view thru one of the gang dies shown in detail.

Figure 5 is a partially sectioned elevational view of one of the gang punches, the sectioned portion showing the shearing and forming punch in detail.

Figure 6 is a partially sectioned elevational view of one of the eccentric arms used in actuating the gang punches, the sectioned portion of said view showing the means pro-

vided of permitting an independent longitudinal movement of an element of said arm.

Figure 7 is a front elevational view of the eccentric disks used for moving the gang punches.

Figure 8 is a top plan view of Figure 7.

Figure 9 is a cross-sectional view of a bottle cap, showing its outline as produced with the punch and die illustrated.

Referring in detail to the drawing, the numerals 1 and 2 illustrate parallel side frames which are bolted to a bed of concrete or the like thru the means 3, and at one end are provided with pillow blocks 4 in which a shaft 5 is cradled, this shaft being retained in position in the pillow blocks 4 by caps 6. Upon said shaft a roll of relatively tough but flexible paper is mounted, said paper being fed to the gang dies thru a system of rolls which will be more fully hereinafter described.

The frames 1 and 2 support a shaft 7 at the ends opposite to the pillow blocks 4 and on this shaft a pulley wheel 8 is rigidly mounted intermediate its length. This shaft is retained in place by the caps 9, and the end which extends from the frame 2 has a fly wheel 10 mounted thereon. The opposite end of the shaft 7 which extends from the frame 1, has a spur gear 11 rigidly secured thereto. An additional shaft 12 is rotatably mounted in the frames 1 and 2 and is secured in place by caps 13 adjacent and somewhat spaced-apart from the shaft 7. The end of the shaft 12 which extends from the frame 2 has a sprocket wheel 14 attached thereto, while the opposite end of said shaft has a relatively large gear 15 permanently mounted thereon, said gear being in continuous mesh with the spur gear 11. The frames 1 and 2 are provided with ledges 16 at various positions in order to support the foot plates 17 of additional frames 18 and 18^a, the foot plates of said frames being secured to the ledges 16 by bolts 19. These additional frames 18 and 18^a are provided with substantially U-shaped guides 20, 21 and 22 in which vertical channels are formed. The guides 20 and 21 are arranged side by side, and the guide 22 is positioned below the guide 21.

The guide members 22 slidably support the ends of spindles 24 and 25 on each of which a roller 26 and 27 is rigidly mounted, the

peripheries of the rollers being normally retained in mutual yieldable contact. The roller 27 has approximately half its periphery immersed in water which is contained in a longitudinal tank 28, the latter being supported beneath the roller 27. The sheet material or a paper from the roll 29 is trained about part of the periphery of the roller 27 and rides between the rollers 26 and 27, and its lower surface is moistened as the periphery of the roller 26 accomplishes this purpose. An additional roll 30 is mounted on a shaft 31 at the corners of the frames 18 and 18^a, this roller supporting said paper or sheet material and also changes its course so that after passing from the periphery of the roll 30 to where it enters between the rolls 32 and 33, it reverses its surfaces so that the surface which was originally at the bottom is transposed and becomes the upper surface. The roll 33 mounted in the guides 21 lies beneath the roll 32 and a portion of its periphery is continually immersed in a tank of water 34 in a similar manner as the roller 27. These guide members 20, 21 and 22, are provided with caps to prevent inadvertent pulling out of the shafts 24, 37, and 38, supporting their individual rolls, and the caps 35 surmounting and bolted to the guide members 20 and 21 are provided with springs 36 which urge the shafts 37 and 38 downwardly so that the peripheries of the rolls 32 and 42 mounted on these shafts will movably contact with the peripheries of the lower rolls 33 and 39, the latter two rolls being mounted in spindles 40 and 41, respectively. The rolls 39 and 42, the latter being mounted above the roll 39, serve as friction rolls for feeding the paper toward the gang dies. The shaft 41 on which the roll 39 is mounted, has an end which extends beyond the frame 18^a and to said end a bevel gear 43 is secured, this bevel gear being in mesh with an additional gear 44 which is mounted on a shaft 45. The latter constitutes a rotatable vertical member journaled near its upper and lower ends in extension of the frame 18^a and has a friction pulley 46 mounted on its lower end. This friction pulley is slideable longitudinally on the shaft 45 and is provided with a sleeve 47 which is rigid with the pulley and is secured to the shaft by a set screw 48. A stud 49 extends from the lower arm of the frame 18^a in a horizontal direction and rotatably supports a disk 50 on which a friction surface 51 is provided, the periphery of the pulley 46 being also provided with friction material in order to insure frictional contact at all times with the face 51 of the disk 50. The stud 49 which supports the disk 50 has a sprocket wheel 52 rigidly secured thereon between the disk 50 and the frame 18^a and is connected thru a sprocket chain 53 to the sprocket wheel 14, the latter being rigidly mounted on the end of the shaft 12. Upper horizontal guide arms 54 and lower guide arms 55 are provided on the main frames 1 and 2, the arms 54 being directly superimposed over the arms 55. The guide channels between the upper arms rotatably support shafts 56 and 57 upon which parallel and adjacent feeding rolls 58 and 59 are mounted. These shafts 56 and 57 extend slightly beyond the frame 2, the extending end of the shaft 56 being provided with a gear 60, while the opposite shaft 57 has a gear 61 secured thereon which meshes with the gear 60, the shaft supporting said gear 61 also having a sprocket wheel 62 rigidly mounted thereon. The channel between the arms 55 on the lower portion of the frame rotatably support a pair of shafts 63 and 64 which have rolls 65 and 66, respectively, mounted thereon. The rolls mounted on the shafts 56, 57, 63, and 64, have their peripheries retained in yieldable position by the caps 67 beneath which coil springs 68 are mounted. The roll 65 is in synchronous rotation with its upper roll 59 thru a bevel gear attached to the end of the shaft 63 which extends beyond the frame 2, the sprocket wheel 63^a on the shaft 63 being connected to the sprocket wheel 62 by a sprocket chain 69. These rolls 58, 59, 65, and 66, are actuated independently of the remainder of the feeding mechanism mounted on the frames 18 and 18^a and have a movement which serves to intermittently rotate the rolls, the linear distance of movement being equal to the diameter of the blank to be punched from the sheet material. This intermittent movement of the rolls 58 and 59 is accomplished thru a crank mechanism which comprises a cap 70 rigid with the shaft 12 which extends from the frame 1, and an eccentric stud 71 extending from this cap is joined to one end of a rod 72. The opposite end of this rod 72 is secured to a stud 73, the latter being mounted on a disk 74 off-set from its rotational axis. Guide bars 75 are rigidly mounted on the face of this disk and have cap plates secured to their end which rotatably retain a threaded stud 76 in place, this threaded stud being rotatable thru a knob 77. A block 78 is slideable between the bars 75 and has a threaded opening in which the screw stud 76 is engaged. A pin 79 extends from one side of the block 78 and has one end of a rocker arm 80 connected thereto. This rocker arm extends angularly upward and has its upper end formed into a rack 81 whose teeth engage a gear 82 rotatably mounted on the end of the shaft 57 which extends from the frame 1. A ratchet wheel 83 is rigidly mounted on the shaft 57 between the gear 82 and the face of the frame 1. One face of the gear 82 has a pin 84

projecting therefrom on which a pawl 85 is mounted, the pawl being engageable with the teeth of the ratchet 83 to accomplish intermittent rotation of the shaft 57 and the roll 59. An extension 86 of the upper guide bar 54 has a round-headed plunger 87 mounted therein which is extended by a coil spring 88 within a chamber in said extension. The tip of the plunger engages the face of the rack 81 and urges the teeth of the same into mesh with the teeth of the gear 82.

Recesses are formed in both frames 1 and 2 between arms 54 and 56 and receive the bed plate 89 of the gang dies. The bed plate of the gang dies is retained in place by passing bolts 90 thru the ends. These bolts are shouldered and supported at their opposite ends on a triangular bracket 91. The bolts extend in a horizontal direction and are shouldered where one end passes thru the bed plate of the gang die and is secured in place by suitable nuts. The remaining lengths of these bolts between the bed plate 89 and the triangular bracket 91 are exposed and support a movable punch head 92 in which the gang punches are mounted. The rear face of the movable punch 92 is provided with spaced-apart ears 93 near both of its ends between which one end of the eccentric rods 94 are mounted, these eccentric rods being in engagement with a pair of eccentrics 95 lying adjacent to the adjacent sides of the frames 1 and 2. By virtue of the eccentrics 95, the movable head 92 is capable of being horizontally actuated thru a slight distance when the machine is in operation. The gang dies mounted on the bed plate 89 comprise a longitudinal body 96 which extends horizontally across the width of the machine and is secured on the bed plate by bolts 97. The shearing die for cutting the blanks from the sheet material comprise an annular flanged collar 98 whose internal periphery 99 presents the shearing edge, the shearing edge on said die being raised above the face of the body 96. The portion of the body adjacent the internal periphery 99 has a convexly curved surface 100 which extends toward the center. The members 98 are aligned in a horizontal plane and in this machine are shown to the number of eight, each of these members 98 being identically constructed. Within each of the collars 98, a flange 101 is slidably mounted in a recess 102, the flange having a concave face 103 on one side, the side opposite to this face having a stud 104 on which a spring 105 is mounted. A nut 106 on the threaded end of the stud 104 permits adjustment of the flange and the latter is retained yieldably extended by the spring 105.

The stripping and forming punches shown in Figure 5 are of the same number as the

dies and comprise a relatively long shank 107, said shank having a threaded end which passes thru the movable head 92 and is anchored therein by a nut 108. The forward end of the shank is enlarged into a sleeve-like member 109 whose external periphery provides the shearing element, said periphery being registerable in the collar 98. Within the chamber 110 of the sleeve 109, a forming head 111 is retained. The latter has a stem 112 which is slidably mounted in the shank 107. This stem passes entirely thru the shank and has an eye 113 at its opposite end. The outer end of the forming head is provided with a shoulder 114 having the identical curvature as the portion 100 of the die. The face of the plunger head is concaved as indicated by the numeral 115 and is adapted to provide a seat for a floating punch 116 whose face 117 has a convex curvature the same as the concave curvature 103 on member 101. This floating punch 116 has a stud 118 slidably mounted in the forming punch and is retained in place by a pin 119 and normally extended by a spring 120, the latter being housed in a recess formed in the head 111. The eyes 113 which are eight in number are all mounted on a common shaft 121 which is in turn joined to a connecting arm 122. In order to permit adjustment of the length of the eccentric arms actuating the shaft 121, a novel feature is incorporated. This comprises a plurality of blocks 123 which are mounted on the shaft 121. The enlarged end 124 of the arm 122 receives these blocks which in addition has vertical tapering channels in which wedges 125 are mounted, it being noted that each arm has a pair of channels, the tapering face of each pair of channels being on opposite sides of the same. These wedges are surmounted by studs with which nuts are engageable. By drawing down one of these wedge blocks and loosening the opposite one, a longitudinal displacement of the block 123 becomes possible, thus increasing and decreasing the length of the arm. The arms 122 constitute solid bars substantially circular in cross section. At a position intermediate their length threads 126 are formed which engage a nut 127. This nut shoulders within a hollow arm 128. The latter has an opening 129 formed therein in which a reduced end 130 of the arm 122 is slidable. A collar 131 is slidably mounted on the reduced end of the arm 122 and between this collar and member 127, a spring 132 is mounted, the latter by engaging the collar 127 fixed to the arm 122, causes the latter to be urged outwardly. The rear end of member 128 is formed into a cradle 133 in which a semi-circular opening is formed. This opening is flanged and is covered by a similar shaped semi-circular strap 134, thus providing an annular opening in which an eccentric disk

110

115

120

125

130

135 is rotatable, this eccentric disk being rigidly mounted on the shaft 12.

The product formed with this machine is shown in cross section in Figure 9 in which is illustrated a crown whose circumferential wall 136 is straight and the cover 137 of the crown is concaved. The flange 138 encircling the circumferential wall is curved outwardly at its outer edge to lie flush upon the rounded edge of a milk bottle to secure the same in a hygienic manner.

The operation of the machine is as follows:

The pulley 8 is connected by a belt to some source of power and the shaft 7 is thus rotated, which in turn causes the shaft 12 to simultaneously rotate in an opposite direction thru the medium of the gears 11 and 15. Rotation of the gear 12 is transmitted to the sprocket wheel 52 mounted on the stud 49 by the chain 53, thus rotating the friction disk 50. The latter being in contact with the periphery of member 43, causes the vertical shaft 46 to be rotated as the sleeve 47 of member 56 is rigidly secured to said shaft. The gear 44 at the upper end of the shaft 45 meshes with the pinion 43 fixed to the shaft 41 by which means the sheet material is fed from the roller 26 to its position between the rolls 39 and 42. The end of the sheet material as it leaves the periphery of the roller 26, passes between the rollers 27 and 26, and as the roller 27 rotates in the tank of water 28, the lower surface of the sheet material will be dampened or moistened. The material then courses about the roll 30 and changes its direction after passing about said roll so that the side which was originally on the bottom will then be at the top. The sheet material then passes between the rolls 32 and 33, the latter of which is also rotatable in a tank of water 34 and will thus moisten the opposite side, it being noted that the material at this stage has both its surfaces moistened. From thence the material passes between the rolls 39 and 42 which constitute the feeding means, the material being retained in frictional contact with the roll 39 by a downward pressure of the roll 42 which is exerted thru the medium of the springs 36. The feeding roll 39 is being continuously actuated thru rotation of the various members heretofore described, and at this point the next successive operation begins. As one row of bottle caps have been blanked and formed, the sheet material is steadily being fed past the roll 39 and before the next row of sheet material is presented in front of the dies, an appreciable slack of sheet material presents itself between the roll 39 and the roll 59, this slack being indicated by the numeral 136. The roll 59 has an intermittent clock-wise rotation, which is accomplished by a reciprocating movement of

member 80. In accomplishing this movement, it is necessary to mount the gear 82 rotatably and free on the shaft 57. The pin 84 mounted on the face of this gear and having a pawl 85 anchored at its outer end 70 which engages the teeth of the ratchet wheel 83, causes this intermittent rotation of the roll 59, the linear travel of the sheet material over this roll being equal and slightly greater in length than the diameter of the caps to be blanked. This rotation of the roll is accomplished when the member 80 is on the downward travel, as when said member is travelling upwardly, the escapement is provided thru the ratchet and pawl 85 as the latter trips over the teeth the ratchet wheel when the arm 80 is on the up stroke. Reciprocation of the arm 80 is had by connecting the lower end of said arm to a block 78, the block being movably mounted on a rocking 84 disk 74. In order to permit adjustment of the linear travel of the rocker, the block is mounted on a threaded stud 76 which is rotatably anchored on the face of the rocking disk 74. By rotating the knob 77, a projection of the threaded stud 76, the block 78 may be adjusted nearer to, or farther away, from the rotational axis of the disk. Arcuate action of the disk is accomplished thru members 72 one end of which is attached to a stud 73 on the disk 74, while the opposite end is secured to a crank pin, the latter forming a projection of a cap 70. The active travel of the bar 80 is regulated so that the latter is on its outward stroke 100 immediately after the punches and forming dies have completed production of a row of caps. The main body 98 of the blanking and forming dies is rigidly and securely mounted on a vertical face of a base 89 and 105 spans across the width of the machine between the frames 1 and 2. The internal periphery 99 of the shearing collars 98 receive the cutting edge of the sleeves 109 forming the blanking dies. These sleeves 110 are rigidly mounted and travel with a movable head 92 which is slidably secured at both its ends and is guided on members 90. This movable head contacts with the cutting edge on the collars 98 in advance of the forming dies, which will be hereinafter described. The movable head is advanced and retracted so that the sheet material proceeding between the gang dies and the shearing sleeves may be sheared or blanked before being formed into the shape shown in Figure 9. This is accomplished by setting the eccentric disks 95 in advance of the disks 135 which provide an actuating means for the forming punches which begin to perform immediately after the blank has been sheared. It will be noted that thru the arms 94, a movable head 92 is moved independently of the stem 112, the latter being used to actuate the forming punches. When cut 120

ting and blanking edge of the sleeves 109 have entered and contacted with the internal edge 99 of the collars 98, the travel of this head is then completed. Further rotation 5 of the shaft 12 causes the eccentrics 135 to further advance the floating punches 116, urging the blanked sheet material to seat itself upon the concave surface 103 of the floating die head 101. As the heads 111 10 steadily advance, member 101 will be depressed into the recess 102 and the shoulder 114 will seat the sheet material blanked upon the curved face 100 and form the die into the shape shown in Figure 9. From 15 this point on, both the cutting sleeves anchored in the head 92 and member 111 will be simultaneously retracted to their opposite position. In order to permit slight and minute adjustment of the lengths of the 20 arms which reciprocate the stem 112 simultaneously, said arms are made extensible, and the members 128 of said arms are open at the sides in order to permit manipulation of the collar 127. By rotating this collar 25 in either direction, the completed overall length of the arm may be varied. In addition, the blocks 123 in which the shaft 121 is journaled are also made adjustable and may be moved longitudinally. This adjustment 30 of the blocks 123 is accomplished by jamming one of the wedge pins 125 down and tightening the same while the other or opposite wedge pin is lifted the corresponding distance. This becomes possible thru 35 the inclined surface on the wedges. When desired, a plate covering the collars 98 of the dies may be placed on the machine in order to facilitate the stripping of the finished caps from the punches as the latter 40 are being retracted.

We claim:—

1. In a machine for producing caps having the essential characteristics of a crown and a curved annular rim, a pair of frames, a die body rigidly mounted between said frames, a blanking punch and a forming punch, the blanking and forming punches being independently reciprocable, the forming punch being slidable in the blanking punch. 45
2. In a machine for producing caps having the essential characteristics of a crown and a curved annular rim, spaced apart frames, a shaft for supporting a roll of sheet material, rolls mounted one above the other and in mutual yieldable contact, means for moistening one surface of the paper, means for reversing and moistening the opposite side of the paper, a die body supporting gang dies, movable blanking punches, and independently movable forming punches mounted within the blanking punches. 55
3. In a machine for producing caps having the essential characteristics of a crown and a curved annular rim, spaced apart frames, a longitudinal body rigid on the frames, a die head removably mounted horizontally on said body, annular collars removably mounted on a vertical face of the die head, the latter having recesses within the area of the collars, flange heads slid- 60
4. In a machine for producing caps having the essential characteristics of a crown and a curved annular rim, frames supporting blanking and forming dies, horizontal reciprocating blanking punches, horizontal reciprocating forming punches mounted independently movable in the blanking punches, a shaft, eccentric disks on said shaft adapted to reciprocate the blanking punches, additional eccentric disks mounted on said shaft and adapted to reciprocate the forming punches within the blanking punches and independently of the blanking punches, means for intermittently feeding the material over the dies, and means for varying the length of the sheet material being fed to the dies. 70
5. In a machine for producing caps having the essential characteristics of a crown and a curved annular rim, frames supporting a gang die, flanged collars removably mounted on the vertical face of the gang die, the internal periphery forming the shearing edge, means within the confines of the collars for forming a crown on the blank, gang blanking punches, a movable head supporting the blanking punches, additional crown forming punches slidably mounted in the blanking punches, eccentric disks mounted on a shaft, rods engaging said disks and connected to the head, said rods being adapted to reciprocate the head and blanking punches, means for reciprocating the forming punches independently, means for successively moistening the surfaces of the sheet material, and means for feeding the sheet material in front of the dies. 80
6. In a machine for producing caps having the essential characteristics of a crown and a curved annular rim, a pair of spaced apart frames, a longitudinal body spanning said frames, a die head mounted thereon, removable collars mounted on the vertical face of said die head, an annular recess formed in the confines of the collars, a flange head slidable in said recesses, means on said flange for producing a convex surface on the crown of the cap, means on the die head within the collars for curving the rim of the cap, punches cooperative with the collars being adapted to produce circular blanks, additional punches being adapted to form the crown by depressing the flange heads and register in the recesses and means for feeding sheet material to the dies. 90
7. In a machine for producing caps having the essential characteristics of a crown and an upwardly curved annular rim, frames, a longitudinal body rigid on the frames, a die head removably mounted horizontally on said body, annular collars removably mounted on a vertical face of the die head, the latter having recesses within the area of the collars, flange heads slid- 100
8. In a machine for producing caps having the essential characteristics of a crown and an upwardly curved annular rim, frames, a longitudinal body rigid on the frames, a die head removably mounted horizontally on said body, annular collars removably mounted on a vertical face of the die head, the latter having recesses within the area of the collars, flange heads slid- 110
9. In a machine for producing caps having the essential characteristics of a crown and an upwardly curved annular rim, frames, a longitudinal body rigid on the frames, a die head removably mounted horizontally on said body, annular collars removably mounted on a vertical face of the die head, the latter having recesses within the area of the collars, flange heads slid- 120
10. In a machine for producing caps having the essential characteristics of a crown and an upwardly curved annular rim, frames, a longitudinal body rigid on the frames, a die head removably mounted horizontally on said body, annular collars removably mounted on a vertical face of the die head, the latter having recesses within the area of the collars, flange heads slid- 130

able in said recesses, a concave surface on the flange heads being adapted to produce a convex curvature on the crown of the cap, said heads when depressed being adapted 5 to form the crowns of the caps, a stud on said flange heads slidable in said die head, springs on said studs being adapted to extend the flange heads when depressed, and punches cooperative with the collars and 10 flange heads for blanking and forming crowns on the caps.

7. In a machine for producing caps having the essential characteristics of a crown with a convex surface and a curved annular 15 rim, frames, a longitudinal member joining said frames, a die head on said member, annular collars mounted in recesses on the vertical face of the die head, additional recesses formed concentrically within the collars 20 areas, flange heads slidable in said recesses, a concave face on the flange heads being adapted to produce the convex curvature on the crown of the cap, the annular area between the concentric recess and the 25 internal rim of the collars having a curved face, said curved face being adapted to produce a curved rim on the cap, blanking and forming punches co-operative with the collars and the slidable flange to form a 30 crown and an annular rim from a flat blank, a stud on a slidable flange and a spring on said stud for lifting the flange when the latter is depressed.

8. In a machine for producing caps having the essential characteristics of a crown and a curved annular rim, a pair of frames, a die head mounted horizontally between the frames, collars having an internal annular shearing edge, bolts fixed on said frames 35 parallel thereto, a movable head slidable on said bolts, sleeve-like members cooperating with the shearing edge of the die forming blanking punches, punches slidably mounted in the sleeve-like members adapted to 40 form the crown of the cap, a shaft, eccentric disks mounted on said shaft, rods coupling the movable head and eccentric disks, the latter being adapted to reciprocate the blanking punches thru the medium of the 45 rods, and additional means for independently moving the forming punches in the blanking punches.

9. In a machine for producing caps having the essential characteristics of a crown and a curved annular rim, a pair of frames, a die head mounted horizontally between the frames, collars having an internal annular shearing edge, bolts fixed on said frames parallel thereto, a movable head slidable on said bolts, sleeve-like members fixed in said movable head on a vertical face thereof, the outer edge of said members being co-operative with the collars to form 50 annular blanks, forming heads slidably mounted in said members, stems on said 55 forming heads passing thru the sleeve members, a curved shoulder on the faces of the forming heads, said shoulder being adapted to co-operate with the die area within the collars to produce a crown on the cap, means 70 for producing a convex curvature on the crown surface, a shaft, eccentric disks on said shaft coupled to and adapted to reciprocate the movable head and additional eccentric disks coupled and adapted to reciprocate the forming punches, the latter being independently movable in the sleeve members, and means for retracting or extending the forming punches in the sleeve members 75 as a unit.

10. In a machine for producing caps having the essential characteristics of a crown and a curved annular rim, a pair of frames, a die head mounted horizontally between the frames, collars having an internal annular shearing edge, bolts fixed on said frames parallel thereto, a movable head slidable on said bolts, sleeve-like members fixed in said movable head on a vertical face thereof the outer edge of said members being co-operative with the collars to form annular blanks, forming heads slidably mounted in said members, stems passing thru said sleeve members and rigid with the forming heads, eyes at the ends of said stems, a shaft passing thru the eyes of said stems, an additional shaft, eccentrics mounted on said shaft adapted to reciprocate the movable head and sleeve members, additional eccentric disks, rods coupling the shaft passing thru the eyes and the eccentric disks, the first-named eccentric disks being set in advance of the last-named disks permitting the sleeve members to engage the die collars and shear the blank before the forming heads co-operate 90 with the die, means on the rods reciprocating the forming heads for adjusting the length thereof, and means intermittently feeding the sheet material to the position in front of the blanking collars.

11. In a machine for producing caps having the essential characteristics of the crown and curved annular rim, a pair of frames, a die head mounted horizontally between the frames, collars having an internal annular shearing edge, bolts fixed on said frames parallel thereto, a movable head slidable on said bolts, sleeve-like members fixed in said movable head on a vertical face thereof, the outer edge of said members being cooperative with the collars to form annular blanks, forming heads slidably mounted in said members, floating punches mounted in the punches, said floating punches having a convex face, the latter being cooperative with the die to form a convex curvature of the crown of the cap, stems on said forming heads, a shaft coupling the rear ends of said stem, eccentric disks adapted to reciprocate the movable head and sleeve members 100 105 110 115 120 125 120 125 120 125 120

mounted thereon, additional eccentric disks being adapted to independently reciprocate the forming head in the sleeve members, eccentric rods connecting the disks with the coupling shaft of the forming punches, said eccentric rods comprising hollow arms, connecting arms slidable in said hollow members, a threaded portion in said connecting arms, a nut engaging said thread, a spring mounted in said hollow arms on the connecting arm being adapted to extend the latter, blocks on the ends of the connecting arms, and means for adjusting the position of said blocks with respect to the connecting arms.

12. In a machine for producing caps having the essential characteristics of the crown and curved annular rim, a pair of frames, a die head mounted horizontally between the frames, collars having an internal annular shearing edge, bolts fixed on said frames parallel thereto, a movable head slidable on said bolts, sleeve-like members fixed in said movable head on a vertical face thereof, the outer edge of said members being cooperative with the collars to form annular blanks, forming heads slidably mounted in said members, floating punches mounted in the punches, said floating punches having a convex face, the latter being cooperative with the die to form a convex curvature of the crown of the cap, stems on said forming heads, a shaft coupling the rear ends of said stem, eccentric disks adapted to reciprocate the movable head and sleeve members mounted thereon, additional eccentric disks being adapted to independently reciprocate the forming head in the sleeve members, eccentric rods connecting the disks with the coupling shaft of the forming punches, said eccentric rods comprising hollow arms, connecting arms, a nut engaging said thread, a spring mounted in said hollow arms on the connecting arm being adapted to extend the latter, blocks on the ends of the connecting arms, said blocks being mounted on the coupling shaft of the forming punches, blocks being retained in the ends of the connecting arms, tapered slots passing thru said connecting arms, wedges mounted in said slots, said wedges when alternately inserted or lifted in the slots being adapted to shift the blocks longitudinally on the connecting arms, and means for feeding the sheet material to the blanking dies.

13. In a machine of the class described having dies and punches therein, a pair of rolls adjacently mounted above the dies, a pair of rolls mounted below the dies, shafts supporting said rolls, a gear on one of said shafts, a bolt mounted on said gear, a ratchet wheel on said shaft adjacent the gear, said

bolt being coactive with the ratchet wheel, and means for engaging said gear to intermittently rotate said shaft.

14. In a machine for producing caps having the essential characteristics of a crown and a curved annular rim, a pair of frames, dies on said frames, blanking punches horizontally reciprocable on the frame, forming punches slidably mounted in the blanking punches and independently reciprocable on the frames, a pair of rolls adjacently mounted above the blanking dies, a pair of rolls mounted below the blanking dies, shafts supporting said rolls, a punch moving shaft, a rocking disk, an eccentric shaft on said punch moving shaft, a rod connecting the rocking disk with the eccentric shaft, a gear rotatably mounted on the shaft supporting one of the upper rolls, a pawl pivoted on said gear, a ratchet wheel rigidly mounted on the shaft adjacent said gear, a rack bar pivoted on the rocking disk, the teeth of the rack bar engaging the gear, said rack bar on the downward stroke being adapted to independently feed the sheet material to the dies, and means for moistening both surfaces of the sheet material successively.

15. In a machine of the class described having dies and punches therein, a pair of rolls adjacently mounted above the dies, a pair of rolls mounted below the dies, shafts supporting said rolls, a punch moving shaft, a rocking disk, an eccentric shaft on said punch moving shaft, a rod connecting the rocking disk with the eccentric shaft, a gear rotatably mounted on the shaft supporting one of the upper rolls, a pawl pivoted on said gear, a ratchet wheel rigidly mounted on the shaft adjacent said gear, a rack bar pivoted on the rocking disk, the teeth of the rack bar engaging the gear, said rack bar on the downward stroke being adapted to independently feed the sheet material to the dies, a pair of vertically aligned rolls at one side of the machine, the sheet material being adapted to pass between said rolls, a water tank mounted beneath the lower roll, the latter being immersed in said tank, said lower roll being adapted to moisten the lower surface of the sheet material, an additional roll adjacent the vertical rolls being adapted to reverse the surface of the paper and an additional pair of vertically aligned rolls, the lower roll of the last named set having a tank thereunder, said lower roll being adapted to be moistened by rotating in said tank, the last named lower roll being adapted to moisten the reverse side of the sheet material, feeding rolls adjacent the last mentioned set of rolls, and means for rotating said feeding rolls.
